United States Patent Office

Des. 192,333

Patented Mar. 6, 1962

192,333

COUPLING TOOL OR THE LIKE

Alfred D. Buechler, Prairie Village, Kans., and Newell Horn, 6311 W. 72nd St., Overland Park, Kans.; said Buechler assignor to said Horn

Filed Jan. 11, 1960, Ser. No. 58,994

Term of patent 14 years

(Cl. D54—13)

Fig. 1.

Fig. 2.

Fig. 3.

FIG. 1 is a side elevational view of a coupling tool or the like, showing our new design;

FIG. 2 is a top plan view thereof; and

FIG. 3 is an end elevational view thereof taken from the left of FIG. 1.

Our design for the coupling tool disclosed is characterized by the specific configuration of the jaw portions.

We claim:

The ornamental design for a coupling tool or the like, as shown and described.
